DESIGN FOR A VEHICLE

William O. H. Freund, Kansas City, Mo.

Application June 22, 1934, Serial No. 52,275

Term of patent 3½ years

To all whom it may concern:

Be it known that I, William O. H. Freund, a citizen of the United States, residing at Kansas City, Jackson County, Missouri, have invented a new, original, and ornamental Design for Vehicle, of which the following is a specification, reference being had to the accompanying drawing, forming part thereof.

In the drawing:

Fig. 1 is a perspective view of a vehicle, showing my new design.

Figs. 2 and 3 are, respectively, front and rear elevational views of the body member only.

I claim:

The ornamental design for a vehicle, as shown.

WILLIAM O. H. FREUND.
